CLAIM

We claim the ornamental design for a package case, as shown and described.

DESCRIPTION

FIG. 1 is a perspective view of a package case, showing the new design;

FIG. 2 is a front view of the package case of FIG. 1; FIG. 3 is a rear view of the package case of FIG. 1;

(Continued)

FIG. 4 is a left side view of the package case of FIG. 1;
 FIG. 5 is a right side view of the package case of FIG. 1;
 FIG. 6 is a top plan view of the package case of FIG. 1;
 FIG. 7 is a bottom plan view of the package case of FIG. 1;
 and,
 FIG. 8 is a sectional perspective view of the package case of FIG. 1 along the line A-A of FIG. 2.

1 Claim, 8 Drawing Sheets
